DISPENSER

Alexander J. Stanley, North Brunswick Township, Middlesex County, and James Shane Nicholls, Jr., Kingston, N. J., assignors to Industrial Tape Corporation, a corporation of New Jersey

Application August 4, 1948, Serial No. 42,446

4 Claims. (Cl. 242—55.5)

1

This invention relates to a tape supporting, cutting and dispensing device particularly suitable for holding and facilitating the dispensing of rolls of normally tacky and pressure-sensitive adhesive tape.

It is a purpose of the invention to provide an improved tape holder, cutter and dispenser that is compact, attractive in appearance, economical to manufacture, and simple and adequate in operation. It is a further object of the invention to provide a dispenser that permits ready insertion and removal of the tape roll without weakening of materials used economically in dispenser structures. A still further object of the invention is the provision of compact dispensers the main portions of which may be bent from one and the same size of blank to any desired roll size.

Other objects and advantages will be apparent from the following description of one practical embodiment of this invention, particularly when considered in connection with the drawing wherein:

Fig. 1 is a side elevation of a tape holder, cutter and dispenser constructed in accordance with the invention and illustrates its use as a holder of tape rolls prior to removal of the tape;

Fig. 2 is a front plan view of the device shown in Fig. 1;

Fig. 3 is a plan view of the blank used to form the body section of the dispenser;

Fig. 4 is an exploded, partial perspective view illustrating insertion of the roll and closing of the dispenser by attachment of the knife unit to the body unit thereof;

Fig. 5 is an enlarged section through line 5—5 of Fig. 1 showing the double tongue and groove interlocking arrangement utilized to anchor the knife section of the dispenser to its body section and to secure its walls in fixed relation to each other.

Referring more particularly to the figures and drawing it will be apparent that a tape holder, cutter and dispenser made in accordance with the invention can be stamped out with a minimum of waste from a narrow rectangular strip of flat sheet metal and then formed into shape in subsequent operations. The dispenser has a body section 10 and a frontal knife section 11 constituting a bridge.

The body section consists of opposed parallel side walls 12 and 12a joined together at the rear and spaced by a narrow bridge section 13 bent at a 90° angle to the side walls at lines 14 and 14a, respectively. Each side wall is struck inwardly at its center to provide an inwardly projecting tubu-

lar core or roll support 15 of proper diameter to fit within the core C upon which is wound the tape T to be cut and dispensed. The side sections are cut low near their front ends so as to permit insertion of a finger to grasp tape in position for dispensing. To hold the sides of the dispenser in parallel relation and to secure the roll thereby in rotatable fixed position a removable frontal knife section 11 is attached rigidly to the front ends 16 and 16a of the side sections 12 and 12a by suitable anchoring means. This frontal knife section 11 consists of a standard 17 which is bent at right angles near its upper end to provide a platform 18 ending in a knife 19, preferably serrated as illustrated.

The double tongue and groove interlocking arrangement joining the frontal knife section to the body section of the device consists of opposed forward extensions of the side sections bent forward reversely to form slots 20 and 20a directed outwardly and of coacting sideward extensions of the frontal knife section bent backward reversely to form slots 21 and 21a directed inwardly. This arrangement is shown best in Figs. 4 and 5. The forwardly bent tongue 22 of each side wall fits into the slot 21 of the corresponding side of the frontal knife section and the backwardly bent tongue 23 of the frontal knife section on each side in turn fits into the groove 20 of the corresponding side wall. A very rigid structure, secured by four layers of metal (see Fig. 5), is thus provided. A shoulder 24 on the standard portion of the frontal knife section acts as a stop to prevent sliding of that section downwardly beyond a certain point. In cases where it is desired to prevent release of the knife section from the body section permanently or temporarily, the tongues may be crimped after insertion, for instance at 25, so as to provide a secured dispenser-roll structure. The same body section 10 may be used for tape of different width merely by varying the position of bent lines 14 and 14a when stamping that section out and by substituting a frontal knife section 11 of the desired size.

45 The manner in which the dispensing unit may be utilized is believed apparent from the above description, but will be summarized briefly below:

After stamping out and bending, the body section assumes the position illustrated in Fig. 4. At this stage its walls are spread apart, a tape roll T on its core C is inserted between the roll supports, the side sections 12 and 12a are bent toward each other and the frontal knife section 11 is slid downwardly against the side sections 12 and 12a until halted by the shoulder 24. The

dispenser is now as illustrated in Figs. 1 and 2 and in condition for use. It is prevented from collapsing by the roll and roll supports and from spreading apart by the frontal knife section. Tape may be withdrawn from the roll, cut across the knife 19, and the remaining tape and anchored to the platform 18 to provide tape ready for use. After a roll of tape has been used up, it may be replaced readily by simply removing the frontal knife section 11, taking out the old roll of tape, entering a new one, and re-establishing the frontal knife section in its old position.

The dispenser stands readily on any flat surface and may be made compact enough to permit carrying it about ready for use without undue bulk. Many variations of the invention in addition to the embodiment described above by way of example only, will occur to those skilled in the art and are considered embodied within the inventive concept.

The claims are:

1. A device for dispensing adhesive tape from the roll, comprising opposed inherently spreadable side portions apart from each other, roll supporting means depending from and arranged between said side portions, tongue and groove means on said side portions, and a frontal removable section spaced from said roll supporting means including a knife and lateral tongue and groove means, opposed to and cooperating with said first-mentioned tongue and groove means and adapted to hold the elements of said device in fixed position to each other when positioned thereon and prevent spreading of said otherwise spreadable side portions in use.

2. A device for dispensing adhesive tape from the roll, comprising a body portion including inherently spreadable side walls, a bridge portion spacing them, roll supporting means depending from and arranged between said side portions, lateral tongue and groove means located on said side walls away from said bridge portion and spaced from the center of said roll supporting means by a distance substantially greater than the radius of any roll that can be held therein, and a removable bridge portion, including tongue and groove means, opposed to and cooperating with said first-mentioned tongue and groove means to prevent spreading of said side walls in use.

50

3. A device for dispensing adhesive tape from the roll, comprising a body portion comprising inherently spreadable side walls including cutout means for a finger space, a bridge portion spacing said side walls, lateral slide means based on a tongue and groove portion located on said side walls away from said bridge portion spaced from the center of said roll supporting means by a distance substantially greater than the radius of any roll that can be held therein, and a removable bridge portion including a knife and lateral tongue and groove means slidable on said slide means and including stop members to prevent spreading of said side walls in use.

4. A device for dispensing adhesive tape from the roll comprising a body portion comprising inherently spreadable side walls including cutouts for finger space, a narrow bridge portion spacing said side walls, roll supporting means depending from and arranged between said side portions adapted to hold a roll of tape in position so as to prevent approachment of said side walls, tongue and groove means located laterally on said side walls away from said bridge portion spaced from the center of said roll supporting means by a distance substantially greater than the radius of any roll that can be held therein, and a removable bridge portion slidable on said tongue and groove means, including a knife, and including also lateral tongue and groove means opposed to said first-mentioned tongue and groove means and cooperating with said first-mentioned tongue and groove means and with said roll supporting means to lock said device rigidly and prevent 35 relative movement of said side walls in use.
